UNITED STATES PATENT OFFICE.

DONALD S. BARROWS, OF ROCHESTER, NEW YORK.

SIDE FRAME.

Application filed March 10, 1927. Serial No. 174,287.

This invention relates to side frames adapted for railway car trucks and, more especially, to such frames provided with depending jaws or pedestals at the ends thereof adapted to straddle associated journal boxes and means for adjusting said pedestals with respect to said boxes.

The principal object of my invention, generally considered, is the provision of a side frame formed with pedestals or jaws at either end thereof and preferably wedge-shaped liner means attachable to the inner faces of said jaws for adjusting the effective distance therebetween, whereby associated journal boxes are, not only securely held in position, but the distance between the journal boxes at opposite ends of the frame, which determines the wheel base of the truck, may be adjusted.

20 An object of my invention is the provision of a side frame particularly adapted for railway car trucks and having jaws depending from opposite ends thereof formed for attaching associated journal boxes to the frame and means adapted to be secured to the faces of said jaws normally engaging said boxes for exactly maintaining the effective jaw width.

Another object of my invention is the provision of wedge-shaped adjusting means adapted for slidable engagement with the sloping sides of pedestals or jaws of side frames adapted for receiving associated journal boxes, said means, after adjustment, being 30 securable in position to closely embrace the corresponding journal box and preferably formed with apertures therethrough adapted to receive locking means from the adjacent portions of the pedestals.

40 Other objects and advantages of the invention relating to the particular arrangement and construction of the various parts will become apparent as the description proceeds.

45 Referring to the drawings illustrating my invention, the scope whereof is defined by the appended claims:

Figure 1 is a partial side elevation of one end of a side frame with journal box receiving jaws or pedestals, an associated journal box being illustrated in position as viewed in longitudinal section on the line 3—3 of Figure 2.

50 Figure 2 is a horizontal sectional view on the line 2—2 of Figure 1 looking in the direction of the arrows.

Figure 3 is a longitudinal sectional view on the line 3—3 of Figure 2 looking in the direction of the arrows.

Referring to the drawings in detail, like parts being designated by like reference characters, I have shown one end of a side frame 1 of the cast type provided with depending pedestals or jaws 2 and 3 adapted to straddle or embrace an associated journal box 4. Although only one end of the frame 1 is illustrated, it will be obvious that said frame is preferably symmetrical and provided with corresponding jaws or pedestals 2 and 3 at the opposite end thereof and that another 70 corresponding journal box 4 may be similarly connected at said other end.

In the embodiment illustrated, the jaws or pedestals 2 and 3 preferably slope downwardly and outwardly from the connecting portion 5 of the frame, said portion being adapted to normally rest directly on the top or roof 6 of the associated journal box 4. The sloping inner walls of the pedestals or jaws 2 and 3 are preferably disposed so as to allow some 80 clearance 7 and 8 with respect to said journal box and adjustable liner blocks 9 and 10 are provided for enabling the jaws of the frame to closely embrace and hold the associated journal box. Although a particular construction of these liner blocks is illustrated and will now be described, it is obvious that I do not wish to be limited to the details and changes may be made therein within the spirit and scope of the appended claims.

90 In the embodiment disclosed, each liner block 9 and 10 is formed with a wedge-shaped portion 11, the side walls of which are disposed at an angle corresponding to the inclination of the inner walls of the jaws or pedestals 2 and 3. The outer surface of each liner block is adapted for slidable engagement along the corresponding inner surface of the associated side frame jaw until only the necessary clearance is left between said 100 liner block and journal box. Each liner block is then secured in position by inserting a sufficient number of shims 12 between the base portion or outstanding flange 13 and the corresponding connecting web portion 14 between the transversely spaced webs 15 of the side frame jaw defining longitudinal openings 16 through which the bases 13 of the liner blocks are inserted. After adjustment 105 in place, each liner block may be secured in 110 position by rivets 17 or other suitable securing means, the apertures 18, receiving said

rivets, being longitudinally elongated, as illustrated, to permit the adjustment heretofore referred to.

The journal boxes 4 are preferably formed with the upper portions of their sides shaped to correspond with the shape of the adjacent portions of the jaws and the lower portions substantially vertical or upright to correspond with the adjacent sides of the liner blocks 9 and 10, and may be securely held in place after adjustment and securing of said liner blocks in place by a locking block 19 for each journal box which is slidably arranged in the aperture 16 in the corresponding outer 10 pedestal and passes through the corresponding aperture 20 in the associated liner block 9, the inner end thereof being formed to correspond with and be inserted in a registering recess 21 in the adjacent side of the journal 15 box. The other side of the journal box may be formed with a similar recess 22 so that it is adapted for connection at either end of the frame. After positioning in place, the locking block 19 may be securely held in any 20 desired manner as by means of a bolt or cotter 25 passing through registering apertures in the walls 15 and locking block 19. In order to avoid interference with the upper head of the rivet 17, the lower side of said locking 30 block 19 is formed with an elongated rivet head receiving pocket 24.

From the foregoing disclosure, it will be apparent that I have devised a construction by means of which, not only may the exact 35 jaw width of the journal box pedestals be maintained but, inasmuch as both liner blocks are capable of longitudinal adjustment in the same direction, it is possible to accurately adjust the wheel base of the truck which is determined by the distance between the journal 40 boxes at opposite ends of the side frame. Although a particular form of locking means is shown, used with the liner blocks and passing therethrough, it is obvious that other 45 forms may be employed, if desired. Although each liner block is held in position by a vertical rivet, whereby the necessity for a long rivet receiving slot is obviated, it will be apparent that I do not wish to be limited to 50 the employment of vertically disposed securing means as such means extending through the webs of the pedestals adjacent the boxes and the adjacent portions of the liner blocks may be employed, if desired.

Having now described my invention, I claim:

1. A side frame having jaws adapted to straddle a journal box and means adapted to be secured to the inner surface of one of said 60 jaws, and formed with an outstanding flange adapted to be secured to a supporting web of said jaw, for exactly maintaining the desired effective distance between said jaws.

2. A side frame having jaws adapted to 65 straddle an associated journal box and wedge-

shaped means adapted to be secured to the inner surface of one of said jaws, and formed with a base portion for resting on adjusting shims supported by said jaw, and slidable therealong for accurately maintaining the desired jaw width. 70

3. A side frame having depending jaws sloping outwardly and adapted to receive a journal box therebetween, the upper portion of said box having correspondingly shaped 75 sides for fitting between said jaws, and the lower portion having approximately upright sides, and wedge-shaped liner means adapted for attachment to the sloping surfaces of said jaws, presenting approximately upright inner surfaces to the corresponding sides of the box, and slidable therealong for adjusting the effective distance therebetween for receiving said box. 80

4. A side frame having a pair of jaws at 85 either end thereof adapted to embrace associated journal boxes and means attachable to those surfaces adjacent the sides of the journal boxes for accurately maintaining the fit between said boxes and frame and the desired wheel base, said means having normally horizontal base portions supported by means of said jaws. 90

5. A side frame having a plurality of 95 depending jaws at each end thereof, the inner surfaces of said jaws flaring outwardly, a journal box positioned at each end thereof between the corresponding jaws, and correspondingly formed wedge-shaped members 100 movable along the inclined sides of the jaws between the same and the journal boxes for properly positioning said boxes and maintaining the proper clearance with respect to the frame, said members being connected to the frame with shims therebeneath for holding them at the desired elevation. 105

6. A side frame having a pair of jaws at either end thereof adapted to embrace associated journal boxes, said jaws being formed with longitudinally extending apertures defined by webs of said jaws, the inner surfaces of said jaws sloping downwardly and outwardly and wedge-shaped adjusting means insertable between said jaws and the associated journal boxes, each of said means comprising a base portion insertable through the longitudinal aperture and resting on the lower web portion therearound, shim means positioned between said base portion and said web portion to hold the same in adjusted position, and securing means passing through said base portion, shim means and web for securing said adjusting means in a desired position to hold the associated journal box snugly in place. 110 115 120 125

7. A side frame formed with a pair of jaws at either end thereof adapted to embrace associated journal boxes, the surfaces of said jaws, adjacent said journal boxes, sloping downwardly and outwardly, the outermost of 130

said jaws being formed with longitudinally extending apertures, wedge-shaped liner blocks with these base portions extending through said apertures and resting on the 5 lower webs of the jaw portions, said liner blocks being formed with longitudinal apertures registering with the apertures in the jaws, and locking means insertable through said apertures in the jaws and liner blocks 10 with their ends adapted to engage in corresponding pockets in the associated journal boxes for locking said boxes in place, means for securing said liner blocks to said jaws in adjusted position and means for securing said 15 locking means to said jaws, whereby the associated journal boxes are snugly embraced in the jaws and locked in position with respect thereto.

8. A side frame having a pair of jaws at 20 either end thereof adapted to embrace associated journal boxes, said jaws being formed with longitudinally extending apertures defined by webs of said jaws, the inner surfaces of said jaws sloping downwardly and outwardly, and wedge-shaped adjusting means 25 insertable between said jaws and the asso-

ciated journal boxes, each of said means comprising a base portion insertible through the longitudinal aperture and resting on the lower web portion therearound, and shim 30 means positioned between said base portion and said web portion to hold the same in adjusted position.

9. A side frame formed with a pair of jaws at either end thereof adapted to embrace associated journal boxes, the surfaces of said jaws, adjacent said journal boxes, sloping downwardly and outwardly, the outermost of said jaws being formed with longitudinally extending apertures, wedge shaped liner 40 blocks with base portions extending through said apertures and resting on the lower webs of the jaw portions, said liner blocks being formed with longitudinal apertures registering with the apertures in the jaws, and locking means insertable through said apertures in the jaws and liner blocks with their ends adapted to engage in corresponding pockets in the associated journal boxes for locking 45 said boxes in place.

In testimony whereof I affix my signature.
DONALD S. BARROWS.
